UNITED STATES PATENT OFFICE

2,326,693

RETAINER

Jay J. Sindler, Boston, Mass.

Application January 7, 1942, Serial No. 425,887

1 Claim. (Cl. 70—458)

This invention relates to an improvement in a retainer for keys or other articles having eyes therein, and has as its primary object a retainer on which the articles can be quickly and easily placed and removed and by which the articles are held against unwanted separation from the retainer.

One form of this invention comprises specifically a key retainer having a strip of extensible material with widened ends, preferably but not necessarily sagittate in form, and a perforate plate between the ends of the strip and the key carrying portion which forms a loop suspended from the plate.

This and other embodiments of the invention will be hereinafter described with particular reference to the accompanying drawing, in which

Fig. 1 is a perspective view of the strip which is one element of the retainer; and

Figs. 2 to 5 are perspective views of various embodiments of the invention.

The retainer in each of these embodiments includes the strip 10 and a perforate plate 15. The strip 10 is of extensible material such as rubber, leather, vinylite or synthetic compounds, and terminates in sagittate ends 11, each end including a tip 12 and wings 13. As shown particularly in Fig. 1 the strip is laminated, but it will be understood that the invention is not limited to a strip so constructed; for instance, the strip might be made integral and of the proper thickness.

In the plate 15 is formed a hole 16 through which the ends 11 are passed. The tips 12 and hole 16 are preferably of such dimensions that the tips can be passed freely through the hole. The widened portions or wings 13, on the other hand, are of a width much greater than any transverse dimension of the hole. Since the strip 10 is extensible, however, the ends can be pulled through the hole, the wings 13 first being compressed and, second, after the ends have passed through the hole, resuming their normal status. The plate 15 is thus positioned between the ends 11 and the remainder of the strip on which the keys or other articles are supported. The wings 13, when the ends 11 have been passed through the hole 16, hold the plate and strip assembled and so resist removal of the ends from the hole that this will not take place inadvertently when the retainer is in the hands, pocketbook or pocket.

The embodiments shown in Figs. 2 and 3 differ solely in the way in which the strip and plate have been assembled, the ends 11 being passed through the hole, both in the same direction in

the Fig. 2 embodiment and in opposite directions in the Fig. 3 embodiment. The keys or other articles having eyes therein, exemplified by a single key 17, are strung on the strip by pulling one end 11 through the eyes, either before the strip is assembled with the plate or after one end of the strip has been passed through the hole 16. In both embodiments the article-carrying portion forms a loop from which the articles are suspended. If the eye in the article is small, the strip, being extensible and compressible, can of course be drawn through the eye and the article will usually remain at the position in which it is left. The wings 13, except in the case of articles having extra large eyes, will prevent inadvertent removal of the articles even though the strip 10 and plate 15 are not assembled.

Fig. 4 shows an embodiment of the invention which comprises in addition to the strip 10 and perforate plate 15, a second perforate plate 20. The strip 10 is assembled with the second plate 20 by passing one end through holes 21 and 22 so that strands 23 of the strip, equal in length, extend from one face of the plate. The keys or other articles are then strung on the strip and the ends 11 passed through the hole 16 in the plate 15 as described above. Fig. 4 shows a single key 24 strung on one strand 23, the other strand pressing against the head of the key 24 and holding it in place. However, the key 24 may be strung on both strands 23, a practice particularly desirable when the eye therein is large.

The perforate plate 15 of the embodiment shown in Fig. 5 has not only the hole 16 through which the ends 11 of the strand 10 are passed but a pair of holes 25 and 26. The strip 10 is assembled with the plate 15 by means of the holes 25 and 26 as it is assembled with the plate 20 in the Fig. 4 embodiment so that strands 27 are provided. The key or other article, for example the key 28, is strung on both strands 27 and thereafter the ends 11 of the strip are passed through the hole 16. Preferably the strip 10 of this embodiment is of such length that the keys or other articles are yieldably held in contact with the plate 15 whereby they remain in position and do not clash against each other.

The plates 15 and 20 are here shown as heart shaped but obviously their shape is merely a matter of taste and plates of other shapes can be employed. The ends 11 are preferably sagittate but this forms no part of the invention and it will be understood that while the term "sagittate" is generally used, it includes any enlarged conformation of the ends of the strip that may

be desired for appearance as well as for ease or convenience in manufacture.

While certain embodiments of the invention have been shown and described, it will be understood that the invention is not limited thereto and that other embodiments may be made without departing from the spirit and scope thereof as set forth in the following claim.

I claim:

A device for retaining keys or other articles having eyes therein, comprising in combination

5 a strip of rubber-like elastic material having sagittate ends, the articles being strung on the portion of the strip between such ends, and a plate having a hole therein no transverse dimension of which is greater than one transverse dimension of the sagittate ends, both ends of the strip being pulled through the hole in the plate so that the plate is between the article-receiving portion of the strip and the sagittate ends thereof.

JAY J. SINDLER.
